UNITED STATES PATENT OFFICE

GUIDO HORN, OF WEISSENSEE, NEAR BERLIN, GERMANY

ROUND BRAIDING MACHINE

Application filed December 26, 1929, Serial No. 416,635, and in Germany December 21, 1928.

This invention relates to a round braiding machine and consists particularly therein, that a fixed guide path for the track of the inner carriers is provided, being supported by machine elements situated partly inside the path of the outer carriers and partly outside the path of these carriers. The bearing members of the guide path are preferably connected with each other to, for instance, a channel like machine part. Motion to the inner and the outer carriers is preferably imparted by means of a spokeless ring, equipped with two gear-rims and which is actuated by means of one of the gear rims and which, moreover, supports the outer carriers. With the aid of its other gear-rim the said ring actuates intermediate gear wheels provided at the machine casing, which in turn cause the inner carriers to describe a circular path round the centre of the machine.

In connection herewith the annular machine casing is preferably provided with the groove for the travelling thread-guide levers for reciprocating the threads of the outer carriers in a well known manner across the path of the inner carriers and their threads.

Another object of the invention consists therein, that the fixed casing elements are provided with special so-called corner running-in spools, the threads of which are made to pass into the interior of the machine by means of special guiding devices.

The invention has been represented, by way of example, in the drawings, in which

Fig. 1 is a plan view of a part of a machine in accordance with the invention,

Fig. 2 a sectional view on line 2—2 of Fig. 1,

Figs. 3 and 4 represent, compared with Fig. 2, a somewhat modified embodiment of the invention in two, somewhat larger, part sectional views.

In the drawings 1 represents a casing of a round braiding machine, 2 a gear wheel

actuated by belt drive, 3 a ring supported upon the machine structure and rendered rotatable by means of an intermediate layer of balls 4, said ring being provided with a gear rim 3a at the bottom thereof and adapted to be actuated by the gear wheel 2. This ring 3 supports so-called outer carriers 3b, as well as lugs 3c, which in turn support thread guide levers 5 engaging by means of corresponding rims 6 (Fig. 2) in a groove 7 provided in the annular part 1a of the casing. This groove serves for steering the thread guides in a known manner. 5a shows an external eyelet only of the extreme end of a thread guide lever 5 in one of its end positions, the other parts of this guide lever being omitted, whilst the thread levers 5 in full drawn lines are shown in their other end position in Fig. 2. 8 represents gear wheels meshing with a second gear rim of the ring 3 and rotatably attached to the fixed machine element 1. On the side opposite to ring 3 the gear wheels 8 engage toothed parts of slides 9 of the so-called inner carriers 9a. These slides 9 are made to run along a guide 10a, 10b being supported from different sides by the machine casing 1 whilst leaving slots 11 between the separate parts of the guide. The manner of supporting this guide will be further referred to later.

Upon actuating the gear wheel 2 the ring 3, supporting the outer carriers 3b, is caused to revolve in a direction round the centre of the machine. The ring 3 imparts a rotary motion to the intermediate wheels 8 and these cause the carriers 9a, to describe a circular path round the centre of the machine in a direction opposite to that of the ring 3 and thus of the outer carriers 3b. During the motion of the carriers 3b the thread guides 5 are swung in such a manner, that the threads of the outer carriers 3b once attain an end position causing these threads to attain a position within the surface of a cone the generatrices of which are indicated by

the dotted lines I, Figs. 2 and 4. In the other end position of the thread guide levers 5 the threads of the outer carriers attain the surface of a cone, the generatrices of which are indicated by the dotted line II of Figs. 5 2 and 3.

The parts 10a of the guide of the inner carriers 9a will now at those points, where the threads of the outer carriers essentially move 10 upon the surface of a cone I, be supported from that side 1b of the machine casing, which is situated within the path of motion of the outer carriers 3b, whilst the parts 10b of this guide path will at those points, where 15 the threads of the outer carriers are essentially situated upon the surface of a cone II, be supported from that side 1c of the machine casing, which is placed outside the path of motion of the outer carriers 3b. The parts 20 1b and 1c have, as shown in Fig. 2, been connected so as to form a channel like casing element. From the part 1c extend the particular supports 1d of the guide parts 10b from without into the space between the surfaces of 25 the cones I and II. In other words, the parts 10a of the guide, see Fig. 2 on the left and Fig. 4, are supported from that side of the machine frame, which in the drawings is situated below the surface of the cone I, 30 whilst the parts 10b of this guide are supported by such bearing elements, which in the drawings are situated above the surface of the cone II. The essential point in connection herewith is, that the supports of the 35 intermediate wheels 8 between the ring 3 and the slides 9 of the carriers 9a during the time of the lowest position of the thread guide shown in Fig. 2 lie above the surface of the cone II, whilst they should lie below the surface of cone I, as long as the thread guides 40 occupy their highest positions. The ring 3 is provided with gaps 3d (Figs. 2 and 3) at those points, in which the external eyelet of the thread guide has reached its lowest end 45 position, said gaps forming an extension of tooth gaps of the ring 3 in which the teeth of the intermediate wheels 8 are made to mesh. In these gaps 3d accommodation is provided for the threads of the outer carriers without 50 danger of being damaged by the teeth of the gear wheels 8, when the thread guide is occupying its lowest position. The transfer of the thread guide lever 5 from the position, at which its thread is situated upon the surface 55 of the cone I, to that position, at which the thread is situated upon the surface of the cone II, takes place, as soon as the external eyelet of the thread guide is situated at the interspaces 11 between the parts 1a and 1b. 60 In Fig. 2 the carriers 3b on the ring 3 are situated in the channel formed by the annular parts 1b and 1c. They are thus made to permanently run in a channel.

In the embodiment as shown in Figs. 3 and 65 4 the outer carriers 3b have been attached to

the upwardly extending lugs 3c. In this case, they are covered only at those points where the holders 1d for the guide path have been provided, whereas at those points, where the guide path is being supported by the parts 70 1b, they are exposed.

12a and 12b are spools, which may serve, for producing braids of a square, hexagonal or octagonal cross section by introducing so-called corner running-in threads into the lash 75 formed by the threads of the outer carriers between the cone-surfaces I and II or the intervals between these cone-surfaces and the travelling inner carriers 9a. For this purpose special guide-channels 13a, 13b have 80 been provided which are supported by the bearing elements 1b or 1d of the guide path and so attached thereto between two intermediate wheels 8 that they conduct the threads of their spools into the interior of 85 the machine.

In the Figs. 2 (left) and 4 it has been shown, that a part of the guide path 10 is supported by that side of the machine frame 1 which is placed below in the drawings. 90 This fixed machine frame 1 has been cross-hatched for the purpose of characterizing those parts of the machine frame which belong to each other.

A machine in accordance with this invention possesses the advantage, that essentially the whole of the interior of the machine is left free, whereas the revolving parts of the machine have been reduced to a minimum. It has, moreover, been attained thereby, that 95 the guide body is fixed and that parts, revolving in opposite directions, are not required to glide upon each other. The position of the inner carrier is immaterial; this may also be provided outside the guide, if the latter is 100 displaced towards the interior sufficiently far. Owing to the small number of revolving parts and the inconsiderable mass of the revolving parts the machine runs quite easily. A braking might be effected in a not shown manner 105 immediately upon the ring 3 or also upon the driving wheel 13 or its shaft. A special base plate for the machine is not required. At the groove or channel 1, 1b, 1c feet 14 are provided, which may be utilized as resting points. 110

In the specific machine illustrated sixteen carriers have been shown, as well as four guide track sections held from without and four guide track sections held from within. A machine of this description works two over 115 two. Provided that there were only two gliding track sections of double width available, the sixteen carrier machine would produce a square braid of four over four. Each single thread would be alternately placed above and 120 below four counter running carrier threads, whereby the threads of the outer carriers would pass by on either side of the corner running-in threads of the carriers 12a and 12b. 125

I claim:—

1. In a round braiding machine, a plurality of inner and a plurality of outer carriers, means for causing at least the inner carriers to describe a circular path round the axis of the machine, slides on these inner carriers, a circular guide for these slides, bearing elements for this guide, of which one part supports parts of said guide from the inner side of the path of the outer carriers, another part of the elements supporting other parts of said guide from the outer side of the path of the outer carriers, the bearing elements supported at the inner side of the guide path being disposed on an annular fixed part of the machine leaving free the centre part of the latter of a width not substantially less than the diameter of said guide.

2. In a round braiding machine in accordance with claim 1, the bearing elements of the guide path supporting from the outside being also connected with each other in form of an annular fixed part.

3. In a round braiding machine in accordance with claim 1, the bearing elements of the guide path supporting from the outside being also connected with each other in form of an annular fixed part, thread guiding means for the threads of the outer carriers adapted to swing these threads in such a manner, that they once are situated on one side of the path along which circulate the inner carriers and then again upon the other side of this path, the said annular support of the outer bearing elements of the guide path being provided with a curved groove adapted to move the thread guiding means in the manner stated.

4. In a round braiding machine in accordance with claim 1, a rigid connection of the bearing elements supporting the parts of the guide from within and without, the support for the outer bearing elements being of annular formation.

5. In a round braiding machine in accordance with claim 1, a ring-shaped double gear-rim rigidly connected with the outer carriers, intermediate wheels between this gear-rim and the slides of the inner carriers, and actuating means for this double gear-rim, which also essentially leave free the centre or middle part of the machine, the one of the two rims serving for driving this rim, whilst the second rim serves for causing the inner carriers to describe a circular path through the medium of the said intermediate wheels.

6. In a round braiding machine, a plurality of inner and a plurality of outer carriers, means for causing at least the inner carriers to describe a circular path round the axis of the machine, slides on the inner carriers, a circular guide for these slides, bearing elements for this guide, of which one part supports parts of said guide from the inner side of the path of the outer carriers another part of the elements supporting other parts of said guide

from the outer side of the path of the outer carriers, a fixed support of the guide being provided with a special carrier and a guiding device for the thread of this carrier, the guiding device being adapted to cause the said thread to pass through the said support between an inner carrier and the thread of an outer carrier.

7. In a round braiding machine, a plurality of inner and outer carriers, means for causing at least the inner carriers to describe a circular path round the axis of the machine, a circular guide for these inner carriers, bearing elements for this guide of which one part supports parts of said guide from the inner side of the path of the outer carriers, another part of the elements supporting other parts of said guide from the outer side of the path of the outer carriers, a bearing element supporting from the inside as well as a bearing element supporting from the outside, being provided with a special carrier and a guiding device for the thread of this carrier, this device being adapted to cause the thread to pass through the support of the spool between an inner carrier and the thread of an outer carrier.

8. In a round braiding machine, a spokeless geared ring of large diameter leaving the inner part of the machine free and being held by the outer parts of the machine, means adapted to actuate this geared ring by means of an actuating device also essentially leaving free the inner part of the geared ring, a number of carriers adapted to describe a circular path round the centre of the machine and intermediate elements adapted to transfer independent from the said actuating device the motion of the geared ring to the said carriers.

9. In a round braiding machine in accordance with claim 8, on the geared ring two geared rims, one of which is adapted to be actuated by a source of power, whilst the second geared rim is adapted to actuate the circulating carriers through the medium of the intermediate elements which are designed as gear wheels.

10. In a round braiding machine, a plurality of inner and a plurality of outer carriers, means for causing at least the inner carriers to describe a circular path around the axis of the machine, slides on the inner carriers, a circular guide for said slides, bearing elements for said guide which support parts of said guide from the inner side of the path of the outer carriers and also support other parts of said guide from the outer side of the path of the outer carriers, the bearing elements supporting from the inner side of the guide path and disposed on an annular fixed part of the machine, free of machine parts at its centre.

11. In a round braiding machine, a spokeless geared ring of large diameter leaving the

inner part of the machine free and being held by the outer parts of the machine, means adapted to actuate this geared ring by means of an actuating device also essentially leaving free the inner part of the geared ring, a number of carriers adapted to describe a circular path round the center of the machine and intermediate gear wheels disposed between said ring and said carriers and adapted 10 to transfer the motion of the geared ring immediately to the said carriers.

In testimony whereof I affix my signature.
GUIDO HORN.
